(57) **CLAIM**

The ornamental design for a spittoon funnel for a can, as shown and described.

DESCRIPTION

FIG. 1 is a top perspective view for a spittoon funnel for a can showing my new design;

FIG. 2 is a front side view thereof;

FIG. 3 is a back side view thereof;

FIG. 4 is a bottom plan view thereof;

FIG. 5 is a top plan view thereof;

FIG. 6 is a left side view, the right side view being a mirror image thereof;

FIG. 7 is a bottom perspective view thereof, and,

FIG. 8 is a cross sectional view taken along lines 8-8 from FIG. 4 in an environment of use.

The broken lines in FIG. 8 depict environmental subject matter of a can and forms no part of the claimed design.

1 Claim, 5 Drawing Sheets

FIG. 1

FIG. 8
